[57] CLAIM

I claim the ornamental design for the golf club iron head, as shown and described.

DESCRIPTION

FIG. 1 is a top plan view of the golf club iron head of the present invention;

FIG. 2 is a front elevational view thereof;

FIG. 3 is a back elevational view thereof;

FIG. 4 is a bottom plan view thereof;

FIG. 5 is a right-side elevational view thereof;

FIG. 6 is a left-side elevational view thereof; and,

FIG. 7 is a rear perspective view thereof.
